US00D917262S

(12) **United States Design Patent** (10) **Patent No.:** **US D917,262 S**
(45) **Date of Patent:** **** Apr. 27, 2021**

(54) **HAMMER RECEIVER**

(71) Applicant: **Skitter & Squirt Adventures, LLC**, Missoula, MT (US)

(72) Inventor: **Jack M King, Jr.**, Phoenix, AZ (US)

(73) Assignee: **Skitter & Squirt Adventures, LLC**, Missoula, MT (US)

(**) Term: **15 Years**

(21) Appl. No.: **29/645,213**

(22) Filed: **Apr. 24, 2018**

(51) LOC (13) Cl. **08-07**

(52) U.S. Cl.

USPC **D8/339**

(58) **Field of Classification Search**

(57) **CLAIM**

The ornamental design for a hammer receiver, as shown and described.

DESCRIPTION

FIG. 1 is a perspective view of a hammer receiver as part of an adapter handle.

FIG. 2 is a left-side view of a hammer receiver as part of an adapter handle.

FIG. 3 is a right-side view of a hammer receiver as part of an adapter handle.

FIG. 4 is a bottom view of a hammer receiver as part of an adapter handle.

FIG. 5 is a top view of a hammer receiver as part of an adapter handle.

FIG. 6 is an exploded perspective view of the hammer receiver as part of the adapter handle.

FIG. 7 is a frontal perspective view of a hammer receiver; and,

FIG. 8 is a rear perspective view of a hammer receiver. The broken lines depict portions of the article and environment that form no part of the claimed design.

1 Claim, 8 Drawing Sheets
